UNITED STATES PATENT OFFICE.

AKSEL R. THOMPSON, OF NEW YORK, N. Y., ASSIGNOR TO THE BRUNSWICK-BALKE-COLLENDER COMPANY, OF WILMINGTON, DELAWARE, A CORPORATION OF DELAWARE.

BALL STOP FOR BOWLING ALLEYS.

Application filed April 19, 1920. Serial No. 374,807.

To all whom it may concern:

Be it known that I, AKSEL R. THOMPSON, a citizen of the United States, residing at New York city, in the county of New York and State of New York, have invented certain new and useful Improvements in Ball Stops for Bowling Alleys, of which the following is a specification.

In the game of bowling there are many 10 times when it is desired to play with a limited number of balls and to keep them separate from the usual supply on the rack. This is almost universally the case in match games and in tournaments when the players 15 roll their own balls.

The object of the present invention is to provide an adjustable device which is adapted to be secured on the ball rack to stop the balls at any desired position when they 20 are returned by the ball return to the rack.

In the accompanying drawings illustrating a selected embodiment of the invention.

Fig. 1 is a side elevation of the end portion of one type of ball return showing 25 my invention in full lines in one position on the ball rack and in broken lines in another position;

Fig. 2 is a transverse sectional view through the rack showing the stop in elevation;

Fig. 3 is a sectional view on the line 3—3 of Fig. 2.

Referring to the drawings, 4 is the ball return and 5 is the ball rack comprising the 35 rails 5' suitably spaced apart to form a support for the balls of different sizes which may be used on the bowling alley.

The stop 6 may consist of a substantial block shaped to fit snugly upon and between 40 the rails 5' and of sufficient size to provide for the largest balls. By thus fitting the bottom of the block to the rails and between the rails the block will always maintain its crosswise position on the rack. This stop 45 is secured rigidly in adjusted position on the rack by a center bolt 7 extending through the block and down between the rails, and a cross-bar 8 held by the lower end of the bolt against the under side of the rails. The 50 cross-bar is arched at 8' between its ends to fit between the rails so that it will always be maintained crosswise of the rails. A wing nut 9 on the upper end of the bolt bears against a washer 10 on top of the block and

is tightened to lock the stop in adjusted position on the rack. Cushions 11 of rubber or other suitable material are fastened on both sides of the block, preferably, to prevent engagement of the balls directly with the block.

The stop may be adjusted and secured in any desired position on the rack and it will confine the travel of the balls on the rack to that portion in front of the stop. If only two players are playing on the alley 65 the balls will be stopped close to the front end of the rack convenient for the players, and no time will be lost and no mistake will occur in selecting a ball to roll. If there are a number of balls on the rack, as is 70 usually the case, those balls not being rolled will not be affected by a ball returning to the rack from the ball return. The stop may also be used to separate one size balls from those of another size when only one 75 size is being rolled.

I do not restrict myself to the particular construction of stop herein shown and described although I have found in practice that this form is very satisfactory for the 80 purpose and can be used without injury to the balls or to the rack, but I reserve the right to make all such changes in the form and construction as fairly fall within the scope of the following claims:

I claim:

1. The combination with a bowling alley ball rack comprising a pair of separated rails, of a stop block mounted on the rack and shaped at its bottom to fit upon and between the rails, and means for securing the block rigidly in adjusted position on the rack.

2. The combination with a bowling alley ball rack comprising a pair of separated 95 rails, of a stop block mounted on the rack and shaped at its bottom to fit upon and between the rails, and means engaging said block and said rails for securing the block rigidly in adjusted position on the rack.

3. The combination with a bowling alley ball rack comprising a pair of separated rails, of a stop block mounted on the rack and having a projection at its bottom extending down between the rails, and means 105 for securing the block in adjusted position on the rack.

4. The combination with a bowling alley

ball rack comprising a pair of rails, of a movable stop block resting on the rails, and means for securing the block rigidly in adjusted position on the rack.

5. The combination with a bowling alley ball rack comprising a pair of separated rails, of a stop block having a projection at its bottom extending down and fitting snugly between the rails and engaging the rails on opposite sides of said projection, and means for securing the block in adjusted position on the rack.

10. The combination with a bowling alley ball rack, of a stop block, a cross bar engaging the under side of the rack, a bolt extending through the block and the rack and

engaging the cross bar, and a nut on the upper end of the bolt to tighten the bolt and secure the block in adjusted position on the rack.

20. 7. The combination with a bowling alley ball rack comprising a pair of separated rails, of a stop block mounted on the rack and shaped at its bottom to fit upon and between the rails, a cross bar arranged beneath the rack and arched between its ends to fit between the rails, and a bolt extending through the block and engaging the arched part of the cross bar to secure the block in adjusted position on the rack.

25. AKSEL R. THOMPSON.
